UNITED STATES PATENT OFFICE.

FRED WILLIAM KLUEVER, OF CHICAGO, ILLINOIS, ASSIGNOR TO THE C. F. PEASE COMPANY, OF CHICAGO, ILLINOIS, A CORPORATION OF ILLINOIS.

HINGED RULING-PEN.

1,344,045.

Specification of Letters Patent. Patented June 22, 1920.

Application filed May 10, 1919. Serial No. 296,081.

To all whom it may concern:

Be it known that I, FRED WILLIAM KLUEVER, a citizen of the Republic of Germany, residing at Chicago, in the county of Cook and State of Illinois, have invented certain new and useful Improvements in Hinged Ruling-Pens, of which the following is a specification.

My invention relates to improvements in ruling pens.

An important object of the invention is to provide means whereby one blade or member of the pen may be conveniently shifted to the inner or open position and will be automatically retained in such position.

A further object of the invention is to provide a device of the above mentioned character, which is simple in construction, strong and durable.

Other objects and advantages of the invention will be apparent during the course of the following description.

In the accompanying drawings forming a part of this specification and in which like numerals are employed to designate like parts throughout the same,

Figure 1 is a side elevation of a ruling pen embodying my invention.

Fig. 2 is a central longitudinal sectional view through the same, the movable blade being shown in the closed position.

Fig. 3 is a similar view with the movable blade in the open position, and,

Fig. 4 is a transverse sectional view taken on line 4—4 of Fig. 3.

In the drawings, wherein for the purpose of illustration is shown a preferred embodiment of my invention, the numeral 5 designates a handle, provided with a longitudinally extending opening 6, having its outer end screw-threaded, for receiving the screw-threaded shank 7, of a coupling 8.

The numeral 9 designates a stationary blade, carried by a base 10, provided with a shank 11 having screw-threaded engagement within an opening 12, formed in the coupling 8. The base 10 is provided with a recess 13, receiving the base 14, of a swinging or movable blade 15. The base 14 is pivoted within the recess 13 by means of a transverse pin or pivot element 16, as shown. The base 14 is provided with a cam element 17, having angularly arranged contacting faces 18 and 19.

A compressible coil spring 20 is arranged

within the opening 6, and engages the inner end of the reciprocating plunger 21, disposed within the bore 22 of the coupling 8. This plunger contacts with the end of a secondary plunger 23, provided with a cam head 24, mounted within the recess 13. This cam head is rectangular in cross-section, corresponding to the shape of the opening or recess 13, and is free to slide therein but cannot turn upon its longitudinal axis. The cam head 24 is adapted to alternately contact with the faces 18 and 19, as shown in Figs. 2 and 3.

The blade 15 is provided with a transverse screw-threaded opening 25, receiving an adjusting screw 26, carrying a milled head 27. This adjusting screw also engages within a screw-threaded opening formed in a spring 28, secured to the blade 15, as shown at 29. The screw 26 engages within a recess 30, formed in the blade 9.

As shown in Fig. 2, the cam head 24 is contacting with the face 18, and thereby tends to swing the blade 15 inwardly toward the blade 9, the extent of opening between the points of these blades being regulated by an adjusting screw 25. When it is desired to clean the blades, the blade 15 may be swung to the outer position, as indicated in Fig. 3, and will be held in this position by the cam head 24, contacting with the face 19. It is thus seen that the blade is automatically retained in the closed or open positions when moved thereto.

It is to be understood that the form of my invention herewith shown and described is to be taken as a preferred example of the same and that various changes in the shape, size, and arrangement of parts may be resorted to without departing from the spirit of the invention or the scope of the subjoined claim.

Having thus described my invention, I claim:

A ruling pen of the character described comprising a handle, a relatively stationary blade having a base provided with a shank, a sleeve adapted to connect said shank and said handle, a swinging blade pivotally connected with the stationary blade and provided with a base having angularly arranged faces, a bore formed in said shank, a plunger mounted within said bore and adapted to contact said faces, and means to express said plunger to contact said faces.

comprising, a longitudinally extending opening formed in said handle a bore formed in said sleeve a plunger mounted within said sleeve and contacting said first 5 named plunger, and a spring within the opening of said handle and engaging said second named plunger.

In testimony whereof I affix my signature in presence of two witnesses.

FRED WILLIAM KLUEVER.

Witnesses:

OSCAR O. MERTZ,
C. F. PEASE.
